UNITED STATES PATENT OFFICE

ARCHIE G. DOWELL, OF SAN DIEGO, CALIFORNIA, ASSIGNOR OF ONE-HALF TO FRED A. SUTHERLAND, OF SAN DIEGO, CALIFORNIA

CARBURETOR

Application filed March 16, 1925. Serial No. 15,807.

My invention relates to carburetors, particularly adapted for vaporizing fuel for internal combustion engines, and the objects of my invention are: first, to provide a carburetor of this class particularly suitable for enabling the use of fuel containing an abnormal quantity of water without affecting the smooth operation of the engine with which it is connected; second, to provide a carburetor of this class whereby the conventional vacuum tank and other auxiliary apparatus for drawing or forcing the fuel from the fuel tank to the carburetor is eliminated, the carburetor serving as a vacuum fuel feed means for drawing the fuel from the fuel tank; third, to provide a carburetor of this class in which the air entering the carburetor for vaporizing the liquid fuel therein is uniformly distributed under the body of fuel in the fuel receptacle; fourth, to provide a carburetor of this class adapted to break up any spray or globules of fuel which may be caused by the passage of air through the body of the fuel; fifth, to provide a carburetor of this class in which the fuel after being vaporized and mixed with a small quantity of air is mixed in regulated quantities with a further supply of air at the outlet of the vaporized fuel into the passage of the latter supply of air; sixth, to provide a carburetor of this class which is protected from backfire of the engine cylinders; seventh, to provide a carburetor of this class which is applicable for and may be readily installed on most internal combustion engines now in use; and eighth, to provide a carburetor of this class which is simple and economical of construction proportionate to its functions, durable, easy to adjust, operate, and one which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side elevational view of my carburetor, showing fragmentarily certain connections thereof with an internal combustion engine; Fig. 2 is an end elevational view thereof; Fig. 3 is a plan view thereof taken at 3—3 of Fig. 1; Fig. 4 is a sectional elevational view thereof, taken through 4—4 of Fig. 2, showing certain parts and portions in elevation to facilitate the illustration; Fig. 5 is another sectional elevational view thereof, taken through 5—5 of Fig. 1, also showing certain parts and portions thereof in elevation to facilitate the illustration, and Fig. 6 is a transverse sectional view thereof, taken through 6—6 of Fig. 5.

Like characters of reference refer to similar parts and portions throughout the several views of the drawings.

The preferred embodiment of my invention, as illustrated in the drawings, consists essentially of a fuel receptacle 1, a cover 2 secured to the upper open end thereof, a fuel supply conductor 3, a fitting 4 connecting said supply conductor with the interior of said receptacle, a valve member 5 for controlling the flow of fuel from said supply conductor to said receptacle, a float 6 for actuating said valve member, an air conductor 7 secured transversely to the cover 2 and extending beyond the sides thereof, an air conductor 8 connected with the one end of the air conductor 7 for conducting air heated by the exhaust manifold of the engine to the conductor 7, a plurality of air conductors 9, 10, 11 and 12 connecting the one end of the conductor 8 with the lower portion of the receptacle 1, a perforated plate 13 positioned at the lower end of the receptacle 1 through which the conductor 9 extends, a throttle butterfly valve 14 positioned in the conductor 7 at the outlet end thereof, a choke butterfly valve 15 also positioned in the conductor 7, extensible link means 30, 31 connecting said last mentioned valves, a check valve 16 positioned at the passage connecting the interior of the receptacle 1 with the interior of the air conductor 7, a needle valve 17 for adjusting the flow of the vaporized fuel into the conductor 7, and a valve means for supplying additional air in regulated quantities to the vaporized

fuel in the receptacle above the level of the liquid fuel therein.

The fuel conductor 3, connected with a fuel tank, not shown, is connected, by means of the fitting 4, with the side and near the lower portion of the receptacle 1, however, preferably above the normal fuel level therein. The end of the fitting 4 connected with the receptacle 1 is provided with an enlarged hole 4^a and a valve seat 4^b. In this enlarged hole is reciprocally mounted the valve member 5 which is provided at its outer end with a polygonally shaped portion 5^a, for positioning the valve member centrally within the hole 4^a, and with a conically shaped valve portion 5^b at its inner end, which is adapted to seat against the valve seat 4^b.

The means for uniformly distributing air over the lower portion of the receptacle 1, which consists of the perforated plate 13, is positioned against an annular member 19, which spaces said plate from the bottom of the receptacle. Near the edge of the plate 13 is provided a lug 13^a to which is secured, by means of a screw 20, a pin 21 on which is pivotally mounted, at its outer lower edge, the hollow annular metal float 6. At the pivotal portion of said float is provided an extended valve actuating member or lug 22 which is adapted to engage the outer end of the valve member 5^a, or the portion thereof extending into the receptacle 1, and force the same inwardly against its seat as the float 6 is raised a predetermined distance at its free side.

At the one extended end of the large air conductor 7, secured transversely to the upper side of the cover 2, is pivotally mounted the hollow annular portion 8^a of the hot air conductor 8 which extends to the exhaust manifold or pipe E, the end of the conductor 8 in engagement with the exhaust manifold or pipe being fringed or otherwise spaced therefrom to permit hot air surrounding said manifold or pipe to be taken in through said conductor. The portion of the air conductor 7 around which the annular portion 8^a of the conductor 8 extends is perforated to permit ready passage of the air into the conductor 7.

To the middle portion of the perforated plate 13 is secured the lower open end of the tubular member 9 which is closed at its upper end. Through the side wall of the receptacle 1 extends another tubular member 10 which is secured at its inner end into the side of the upper end of the tubular member 9, thus securing the plate 13 and the float mounted thereon at the lower portion of the receptacle. The tubular member 10 is secured in position by an elbow 11 which is connected at its outer end, by means of a flexible conductor 12, with the normally lower end of the annular portion of the conductor 8. Thus an air passage is pro-

vided between the hot air conductor 8, through the conductor 12, the elbow 11, and the tubular members 10 and 9 to the bottom of the receptacle 1 underneath the perforated plate 13. The conductor 12 is preferably made flexible to adapt the carburetor to different makes of vehicles in which the exhaust manifolds or pipes are variously spaced.

The opposite extended end of the air conductor 7 is connected with the intake manifold 23 of the engine.

Intermediate the ends and in the wall at the lower side of the air conductor 7 is provided an orifice or passage 7^a which connects the interior of the receptacle 1 with the interior of the air conductor 7. At the inner side of the cover 2, through which the passage 7^a extends, is provided a check valve 16 which consists of a casing 16^a secured to a lug on the inner side of the cover, and a ball 16^b within the casing. This check valve is so constructed as to prevent any backfire through the intake manifold 23 of the engine to ignite the charge of fuel within the receptacle 1. Through the air conductor 7 extends a needle valve 17 which is adapted to seat against a seat at the upper end of the passage 7^a.

The portion of the air conductor 7 intermediate the orifice or passage 7^a and the perforated end thereof on which the air conductor 8 is mounted, is considerably reduced substantially forming a Venturi tube to increase the vacuum at the orifice or passage 7^a, as the air from the conductor 8 is drawn into the intake manifold 23. In this reduced portion of the air conductor 7, indicated by 7^b in Fig. 4, is mounted a butterfly valve 15, the rod of which extends upwardly through the wall of the air conductor and is provided at said upwardly extended end with an enlarged portion 15^a which is provided at its upper end with a laterally extending arm 15^b to which is pivotally connected the one end of the choke rod 24.

In the portion of the air conductor 7 between the orifice or passage 7^a and the intake manifold 23 is mounted another butterfly valve 14 which is provided at the upper end of its control rod, extending through the wall of said conductor, with an actuating arm 25 to the outer end of which is pivotally connected the control rod 26, as in the conventional construction.

The arm 25 is provided at its connection with the rod of the butterfly valve 14 with a short arm 25^a which extends at an angle with the main arm 25. The outer end of the arm 25^a is pivotally connected by means of a resiliently extensible link with the outer end of an extensible arm 27 in the form of a screw, which is adjustably secured in the enlarged portion 15^a of the butterfly valve 15 and locked relatively thereto by means of a nut 28. The end of the extensible link 120

connected with the screw 27 is held in engagement with the inner side of the head thereof by means of a compression spring 29. The extensible link consists of link members 30 and 31, the former pivotally connected with the arm 25^a and the latter with the screw 27. The free end of the link member 30 is provided with a tubular portion 30^a into which extends the free end of the link member 31. Within the tubular portion 30^a and between a shoulder at the end of the link member 30 and a head at the end of the link member 31 is positioned a compression spring 32 which tends to contract said link members.

Thus, it will be seen that as the arm 25 is rotated clockwise to close the butterfly valve 14, the butterfly valve 15 is closed proportionately, the proportion being easily varied by the adjustment of the arm or screw 27 relatively to the enlarged portion 15^a of the butterfly valve 15. The resiliently extensible link described permits of the rotation of the butterfly valve 15, by the arm 15^b independently of the butterfly valve 14, thus serving as an independent choke valve.

When the engine is running at low speed the amount of air drawn through the valve 15 will be proportionally low and in order to 30 preserve the correct mixture, the pressure difference between conductors 8 and 7 must be held at a suitable value. This is automatically attained by causing the valve 15 to be closed with valve 14. By suitable adjustment of the setting of valve 15, the pressure difference between conductors 8 and 7 is maintained at the desired value, this pressure difference causing the proper flow of air through the receptacle 1.

40 The valve means for supplying additional air to the vaporized fuel in the receptacle above the normal level of liquid fuel therein is preferably connected with the upper end of the air tube 9 within the receptacle and 45 consists of a cone-shaped or tappet valve member 34 preferably provided with longitudinal stems extending to either side thereof, the inner stem being reciprocally mounted in the wall of the tube 9 as shown in 50 Fig. 4 of the drawings. The cone portion of the valve member is adapted to seat in a boss extending outwardly from the tube. Around said boss is screwably secured a skeleton valve-stem supporting bracket 35 55 provided with a guide portion at its outer end. In this guide portion is reciprocally mounted the other outwardly extending stem of the valve member, thus retaining the valve portion thereof in alignment with its seat. 60 Between the valve or cone portion of the valve member and the guide portion of the bracket 35 is positioned a compression spring 65 for holding the valve portion towards its seat.

35 With the valve means described above,

which may be either connected with a source of hot air through the tube 9 or directly with the atmosphere through the wall of the receptacle 1, the vaporized fuel within the receptacle 1 is mixed with a small amount of air before leaving said receptacle through the passage 7^a where the mixture is again mixed with more air in the conductor 7.

When the valve 14 is closed to the idling speed of the engine, the valve 15 is substantially wholly closed permitting only the gas in the receptacle to be drawn into the engine, the tension of the spring 36 being such as to provide a suitable mixture when the valve 15 is closed, as when throttling the engine, and also when the engine is running at high speed, in which latter case the mixture in the receptacle is richer but is mixed with more air when entering the conductor 7.

Within and at the upper portion of the receptacle 1 is positioned a multiple screen member 18 which consists of an annular member 18^a provided with fine wire mesh screens 18^b and 18^c at its upper and lower ends, the lower one resting preferably at the upper end of the tube 9. As the air from the tube 9 passes to the lower end of the receptacle 1 and upwardly through the perforations in the plate 13 at a rapid rate of speed, beads of fuel are likely to be forced or drawn upwardly. The lower screen 18^b stops the passage of the beads upwardly into the air conductor 7, the screen 18^c causing a further breaking up of the fuel not vaporized, thus permitting only the wholly vaporized fuel to pass through the passage 7^a into the conductor 7. To the annular member 18^a are secured lugs 18^d which extend upwardly therefrom for more readily removing the screen member 18 from the receptacle 1.

It will be here noted that the screen member 18 or any other suitable screen means may be eliminated if the receptacle 1 is considerably lengthened, which latter construction, however, is undesirable in certain carburetor constructions.

At the lower end of the receptacle 1 is provided a drain cock 33 for draining and cleaning the carburetor when desired.

It will be noted with this construction of carburetor, an abnormal percentage of water in the gasoline or other fuel can do no harm to the carburetor and will not affect the smooth operation of the engine, for the reason that the water is thoroughly vaporized and mixed with the fuel vapor. Other impurities or foreign matter in the gasoline or other fuel, such as grit or heavier oils, will remain in the receptacle 1 and will not be carried into the engine, reducing to a minimum injury to the engine parts and carbon deposits in the cylinders of the engine.

Though I have shown and described a particular construction, combination and arrangement of parts and portions, I do not

wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

- 10 1. In a carburetor structure having a fuel receptacle means, a fuel supply conductor communicating with said fuel receptacle means and float and valve means for controlling and regulating the entrance of fuel into said fuel receptacle, an air conductor having its intake end adjacent to an exhaust manifold of a vehicle and its discharge end within said receptacle below the normal fuel level therein, a valve means mounted in said air conductor within said receptacle above the normal fuel level therein communicating from said air conductor into said receptacle for equalizing the pressure therebetween and permitting the discharge of excess air from said air conductor into said receptacle and aiding the evaporation of fuel globules suspended within said receptacle, a second air conductor connected with said first conductor and extending across the top of said receptacle, a Venturi tube integral with said second air conductor, a choke valve at the entering side of said Venturi tube, a valve controlled passage connecting said receptacle with said second air conductor approximately at the point of least pressure within said air conductor for drawing vaporized fuel from said receptacle.
- 20 2. In a carburetor structure having a fuel receptacle means, a fuel supply conductor communicating with said fuel receptacle means and float and valve means for controlling and regulating the entrance of fuel into said fuel receptacle, an air conductor having its intake end adjacent to an exhaust manifold of a vehicle and its discharge end within said receptacle below the normal fuel level therein, a valve means mounted in said air conductor within said receptacle above the normal fuel level therein communicating from said air conductor into said receptacle for equalizing the pressure therebetween and permitting the discharge of excess air from said air conductor into said receptacle and aiding the evaporation of fuel globules suspended within said receptacle, a second air conductor connected with said first conductor and extending across the top of said receptacle, a Venturi tube integral with said second air conductor, a choke valve at the entering side of said Venturi tube, a valve controlled passage connecting said second air conductor with said receptacle approximately at the point of least pressure in said second air conductor for drawing vaporized fuel from said receptacle.
- 30 3. In a carburetor structure having a fuel receptacle means, a fuel supply conductor communicating with said receptacle means and float and valve means for controlling and regulating the entrance of fuel into said fuel receptacle, an air conductor having its intake end adjacent to an exhaust manifold of a vehicle and a discharge end within said receptacle below the normal fuel level therein, a perforated partition positioned transversely in said receptacle, spaced slightly from the bottom thereof, and having a central opening for receiving the discharge end of said conductor for evenly distributing the air from said air conductor substantially radially over the bottom area of said receptacle, a second air conductor connected with said first conductor and extending across the top of said receptacle, a Venturi tube integral with said second conductor, a choke valve at the entering side of said Venturi tube, a valve controlled passage connecting said second air conductor with said receptacle approximately at the point of least pressure in said second air conductor for drawing vaporized fuel from said receptacle.
- 40 4. In a carburetor structure having a fuel receptacle means, a fuel supply conductor communicating with said receptacle means and float and valve means for controlling and regulating the entrance of fuel into said fuel receptacle, an air conductor having its intake end adjacent to an exhaust manifold of a vehicle and a discharge end within said receptacle below the normal fuel level therein, a perforated partition positioned transversely in said receptacle and spaced slightly from the bottom thereof and connected with the discharge end of said conductor for distributing the air from said air conductor over the bottom area of said receptacle, a second air conductor connected with said first conductor and extending across the top of said receptacle, a Venturi tube integral with said second conductor, a choke valve at the entering side of said Venturi tube, a valve controlled passage connecting said second air conductor with said receptacle approximately at the point of least pressure in said second air conductor for drawing vaporized fuel from said receptacle, a valve means mounted in said first named air conductor within said receptacle above the normal fuel line thereof communicating between said first named air conductor and said receptacle for equalizing the pressure therebetween, permitting the discharge of excess air from said air conductor into said receptacle and aid the vaporization of fuel globules suspended in said receptacle.
- 50 5. In a carburetor structure having a fuel

screen baffle means positioned in said receptacle above said valve means therein for further vaporizing the fuel within said receptacle and retarding movement thereof so as to mix with the air from said air conductor.

70 75 80 85 90 95 100 105 110 115 120 125 130

3. In a carburetor structure having a fuel receptacle means, a fuel supply conductor communicating with said receptacle means and float and valve means for controlling and regulating the entrance of fuel into said fuel receptacle, an air conductor having its intake end adjacent to an exhaust manifold of a vehicle and a discharge end within said receptacle below the normal fuel level therein, a perforated partition positioned transversely in said receptacle, spaced slightly from the bottom thereof, and having a central opening for receiving the discharge end of said conductor for evenly distributing the air from said air conductor substantially radially over the bottom area of said receptacle, a second air conductor connected with said first conductor and extending across the top of said receptacle, a Venturi tube integral with said second conductor, a choke valve at the entering side of said Venturi tube, a valve controlled passage connecting said second air conductor with said receptacle approximately at the point of least pressure in said second air conductor for drawing vaporized fuel from said receptacle.

4. In a carburetor structure having a fuel receptacle means, a fuel supply conductor communicating with said receptacle means and float and valve means for controlling and regulating the entrance of fuel into said fuel receptacle, an air conductor having its intake end adjacent to an exhaust manifold of a vehicle and a discharge end within said receptacle below the normal fuel level therein, a perforated partition positioned transversely in said receptacle and spaced slightly from the bottom thereof and connected with the discharge end of said conductor for distributing the air from said air conductor over the bottom area of said receptacle, a second air conductor connected with said first conductor and extending across the top of said receptacle, a Venturi tube integral with said second conductor, a choke valve at the entering side of said Venturi tube, a valve controlled passage connecting said second air conductor with said receptacle approximately at the point of least pressure in said second air conductor for drawing vaporized fuel from said receptacle, a valve means mounted in said first named air conductor within said receptacle above the normal fuel line thereof communicating between said first named air conductor and said receptacle for equalizing the pressure therebetween, permitting the discharge of excess air from said air conductor into said receptacle and aid the vaporization of fuel globules suspended in said receptacle.

5. In a carburetor structure having a fuel

receptacle means, a fuel supply conductor communicating with said receptacle means and float and valve means for controlling and regulating the entrance of fuel into said fuel receptacle, an air conductor having its 5 intake end adjacent to an exhaust manifold of a vehicle and a discharge end within said receptacle below the normal fuel level therein, a perforated partition positioned transversely in said receptacle and spaced slightly 10 from the bottom thereof and connected with the discharge end of said conductor for distributing the air from said air conductor over the bottom area of said receptacle, a second 15 air conductor connected with said first conductor and extending across the top of said receptacle, a Venturi tube integral with said second conductor, a choke valve at the entering side of said Venturi tube, a valve controlled passage connecting said second air 20 conductor with said receptacle approximately at the point of least pressure in said second air conductor for drawing vaporized fuel from said receptacle, a valve means mounted 25 in said first named air conductor within said receptacle above the normal fuel line thereof communicating between said first named air conductor and said receptacle for equalizing the pressure therebetween, permitting the 30 discharge of excess air from said first named air conductor into said receptacle and aiding the vaporization of fuel globules suspended in said receptacle, a screen baffle means positioned within said receptacle above said valve 35 means for further vaporizing the fuel therein and retarding movement thereof so as to mix with the air from said air conductor.

In testimony whereof, I have hereunto set my hand at San Diego, California, this 11th day of March, 1925.
